RAILWAY TRAFFIC CONTROLLING APPARATUS

John M. Pelikan, Chicago, Ill., assignor to The Union Switch and Signal Company, Swissvale, Pa., a corporation of Pennsylvania

Application August 26, 1942, Serial No. 456,175

7 Claims. (Cl. 246—22)

My invention relates to railway traffic controlling apparatus, and particularly to the type known as traffic locking apparatus, for governing traffic movements in both directions over a given stretch of railway track between two opposing manually controllable signals.

Where provision has been made for reverse running on double track, it has been found desirable that the dwarf signals used for controlling the reverse traffic movements shall be of the three-position type if there is a great deal of reverse running. The control for the third position of such a dwarf signal would require an extra control wire for each track, if a common type of two-wire traffic locking circuit arrangement were used which cannot be polarized.

One feature of my invention is the provision of means for controlling a three-position dwarf signal, for reverse running traffic movements on double track, by coded current supplied to a two-wire traffic locking circuit scheme.

I shall describe one form of apparatus embodying my invention, and shall then point out the novel features thereof in claims.

The accompanying drawings, Figs. 1A and 1B, when placed end to end, with Fig. 1A on the left, constitute a diagrammatic view showing one form of apparatus embodying my invention, in which steady direct current of a given polarity is supplied to the conductors of a two-wire traffic locking circuit arrangement for controlling a high signal for the normal direction of traffic movements, and in which direct current, supplied to these two conductors for controlling a three-position dwarf signal for reverse running traffic movements, is coded at frequencies such for example as 75 and 180 times per minute.

Referring to the drawings, the reference characters 9 and 9a designate the track rails of one track of a double-track railway. The normal direction of traffic movements over this track is toward the right as shown in the drawings, which I shall assume is the eastbound direction. The reference characters 10 and 10a designate the track rails of the westbound track, only a portion of which is shown at each end of the drawing.

A manually controlled interlocking layout, including switches 1 and 3 and signals 2R, 2L, 4R and 4L, is shown at the west end of the stretch of track, and a second manually controlled interlocking layout, including switches 5 and 7 and signals 6R, 6L, 8R and 8L, is shown at the east end of the stretch of track. High arm A of signal 2R governs eastbound or nor-

mal direction traffic movements onto the stretch of track, and automatic signals 102, 104, 106 and 108 govern traffic movements over the stretch to signal 6R. A three-position dwarf signal 101 governs westbound or reverse traffic movements on the stretch of track approaching signal 2L of the west interlocking. Dwarf signal 6L in the east interlocking has an upper three-position arm A which governs reverse direction traffic movements over the stretch of track to signal 101. The signals may be of any suitable design, such for example as the searchlight type.

Rails 9 and 9a are divided by insulated joints 11 to form track sections 3T, 101T, 102T, 104T, 106T, 108T and 5T. Rails 10 and 10a are likewise divided by insulated joints 11 to form track sections, only two of which, sections 1T and 7T, are shown. Each track section is provided with a track circuit including a suitable source of current, such as a battery 12, connected across the rails adjacent one end of the section, and a track relay, designated by the reference character R preceded by the reference character for the section, connected across the rails adjacent the opposite end of the section.

The contacts operated by the various relays and other control devices are identified by numbers, each such number having a distinguishing prefix from which it is separated by a dash when the associated contact is shown apart from the relay or other device by which it is operated. The prefix for each of these contact numbers comprises the reference character for the relay or other device by which the associated contact is operated. For example, contact 3TR—30, shown in the lower left-hand corner of the drawing in the circuit for relay 2RH, is identified by the number 30 which is separated by a dash from the prefix 3TR which is the reference character for relay 3TR by which this contact is operated.

The traffic locking circuit arrangement shown on the accompanying drawings embodies a traffic relay 2RFR and a code following lockout relay 2RFL at the west interlocking, and a lockout relay 6LFL and a code following traffic relay 6LFR at the east interlocking. Extending between the traffic relays is a control conductor divided between relay contacts into sections 13—1, 13—2, etc. up to section 13—9, and a return conductor divided into sections 14—1 and 14—2 by contacts 101S—42.

An eastbound traffic control circuit includes lockout relay 6LFL in series with traffic relay 2RFR. This circuit also includes the control con-

ductor and the return conductor, and is energized by constant direct current of a given polarity supplied through an asymmetric unit U_1 from a suitable source of current having terminals BB and OO.

A westbound traffic control circuit for controlling the proceed indication of arm A of signal 6L includes lockout relay 2RFL in series with traffic relay 6LFR. This circuit also includes the control conductor and the return conductor, and is energized by current of the given polarity supplied through an asymmetric unit U_2 from a suitable source of current having terminals B and O. This circuit is periodically interrupted by contact 36 of a suitable code transmitting device 180CT at a suitable frequency which may, for example, be 180 times per minute. As shown in Fig. 1A, device 180CT is connected directly with terminals B and O, and is therefore constantly energized.

A second westbound traffic control circuit for controlling the caution indication of arm A of signal 6L includes traffic relay 6LFR and certain sections only of the control and return conductors. This circuit is periodically interrupted by contact 62 of a second code transmitting device 75CT at a suitable other frequency which may, for example, be 75 times per minute.

The eastbound traffic control circuit becomes closed in response to deenergization of an eastbound route locking relay 1ES in the west interlocking. This route locking relay is controlled by eastbound approach locking relays 2RAS and 4RAS, by switch repeater relays 1RWP and 3NWP, and by track relays 1TR and 3TR.

Approach locking relays 2RAS and 4RAS, associated with arm A of signals 2R and 4R respectively, may be controlled in any suitable manner, such for example as shown for relay 2AS in Letters Patent of the United States No. 2,198,712, granted April 30, 1940 to Harry C. Vantassel, for Railway traffic controlling apparatus.

One manner of controlling relays 1RWP and 3NWP is shown in the drawing. The circuit for relay 1RWP is so arranged that this relay is energized only if the switches 1 at the two ends of the west crossover in the west interlocking are both in the reverse position. The circuit for relay 3NWP is so arranged that this relay is energized only if the switches 3 at the two ends of the east crossover in the west interlocking are both in the normal position.

A circuit for controlling signal relay 2RH for arm A of signal 2R is shown in part, including contact 29 of a signal lever V closed in the reverse position r of this lever, and contact 3TR-30.

A circuit for controlling arm A of signal 2R is shown in part, controlled by a front contact 2RFR-44 of eastbound traffic relay 2RFR, by a front contact 2RH-46 of relay 2RH, and by a back contact 2RFLP-45 of a slow release lockout repeater relay 2RFLP. Relay 2RFLP is energized by a circuit including contact 57 of code following lockout relay 2RFL.

One or the other of the westbound traffic control circuits becomes closed in response to deenergization of a westbound route locking relay 5WS in the east interlocking. Relay 5WS may be controlled similarly to the manner in which relay 1ES is shown controlled in the west interlocking.

If there is no train between signal 2L at the west interlocking and signal 6L at the east interlocking, the first westbound traffic control

circuit will be closed, and traffic relay 6LFR will be energized by current interrupted at a frequency of 180 times per minute.

Both a caution control relay 6LFRP and a proceed control relay 6LAD will therefore be energized by the well-known decoding circuit arrangement shown. Relay 6LFRP is energized whenever relay 6LFR is energized by current of either the 75 or the 180 code, but relay 6LAD becomes energized through a 180 decoding unit 180DU, comprising a resonant rectifier unit, only if relay 6LFR is energized by current of the 180 code. Arm A of signal 6L will therefore be operated to the proceed position by a circuit shown in part, and including front contacts of relays 6LFRP and 6LAD.

If a westbound train has proceeded past signal 101 and occupies section 101T, a signal repeater relay 101PC will be deenergized and a directional stick relay 101S will be energized, causing the second westbound traffic control circuit to be closed. Relay 6LFR will therefore be energized by current interrupted at a frequency of 75 times per minute, and hence relay 6LFRP will be energized but relay 6LAD will be deenergized. Arm A of signal 6L will therefore be operated to the caution position by its circuit including back contacts of relay 6LAD.

Having described, in general, the arrangement and control of the apparatus shown by the accompanying drawings, I shall now describe, in detail, its operation.

As shown by the drawings, all parts are in the normal condition, that is, all track switches are in their normal positions; all signals in both the east and the west interlockings are indicating stop, signals 101 and 108 are indicating caution, and automatic signals 102, 104 and 106 are indicating proceed; all track sections shown are unoccupied; signal lever V is in its normal position; approach locking relays such as 2RAS and 4RAS are energized; route locking relays 1ES and 5WS are energized; relay 3NWP is energized; code transmitting device 180CT is energized, but code transmitting device 75CT is deenergized; relay 101PC is energized; and relays 101S, 2RH, 2LH, 1RWP, 2RFL, 2RFLP, 2RFR, 6LFL, 6LFRP and 6LAD are deenergized.

Of the relays which are energized, relay 3NWP is energized by a circuit passing from terminal B, through contact 15 closed in the normal position of switch 3 at the west end of the east crossover in the west interlocking, contact 16 of switch 3 at the east end of this same crossover, and the winding of relay 3NWP to terminal O. The arm of signal 101 is retained in the caution position by a circuit passing from terminal B, through contact 1ES-17, back point of contact 2LH-18, mechanism of signal 101, contact 19 of relay 101TR, and the back point of contact 2LH-20 to terminal O. Relay 101PC is energized by a circuit passing from terminal B, through contact 21 closed while the arm of signal 101 is in the caution or the proceed position or at any point between these two positions, and the winding of relay 101PC to terminal O.

Relay 1ES is energized by a pick-up circuit passing from terminal B, through contact 22 of relay 2RAS, contact 23 of relay 4RAS in multiple with contact 3NWP-24, contact 3TR-25 in multiple with contact 3NWP-26, contact 1TR-27, and the winding of relay 1ES to terminal O. A stick circuit is also closed for relay 1ES, passing from terminal B, through contact 22 of

relay 2RAS, contact 23 of relay 4RAS in multiple with contact 3NWP-24, contact 28 of relay 1ES, and the winding of relay 1ES to terminal O.

I shall first assume that an eastbound traffic movement is to be made over the stretch of track shown in the drawings. The leverman at the west interlocking will therefore prepare to clear arm A of signal 2R by moving lever V to its r position, thereby completing the circuit for relay 2RH, which is shown in part in Fig. 1A, including contact 29 of lever V, and contact 3TR-30. By referring to the corresponding relay in the Vansassel Patent No. 2,198,712, it will be seen that relay 2RH, upon becoming energized, deenergizes relay 1ES on account of deenergizing relay 2RAS.

When relay 1ES becomes deenergized, its contact 1ES-17 will open the circuit previously traced for signal 101, causing this signal to indicate stop. The circuit for signal repeater relay 101PC will therefore be opened at contact 21 of signal 101, causing relay 101PC to become deenergized.

With relays 1ES and 101PC deenergized, the eastbound traffic control circuit will be completed, passing from terminal BB, through asymmetric unit U1, winding of relay 6LFL, front point of contact 31 of relay 5WS, the various sections 13-1 to 13-9 of the control conductor and through contacts 108TR-32, 106TR-33, 104TR-34, 102TR-35, back point of contact 101PC-37, back point of contact 101S-38, contact 101TR-39, back point of contact 40 of relay 1ES, winding of relay 2RFR, back point of contact 41 of relay 1ES, section 14-1 of the return conductor, back point of contact 101S-42, section 14-2 of the return conductor, and the front point of contact 43 of relay 5WS to terminal OO.

With relay 2RFR thus energized and with relay 2RH energized, a circuit, only a portion of which is shown, will be closed for operating the arm A of signal 2R to the proceed position. The portion of the circuit shown passes through contacts 2RFR-44, 2RFLP-45, and 2RH-46, and through the mechanism of arm A to terminal O.

On account of relay 6LFL being energized by the eastbound traffic control circuit, its contact 6LFL-54 will be open in the circuits for arm A of signal 6L in the east interlocking.

I shall next assume that all parts of the apparatus are again in their normal condition, and that a westbound traffic movement is to be made, that is, a traffic movement in the reverse direction over the stretch of track shown in the drawings. The leverman at the east interlocking will therefore move the lever for signal 6L to a reverse position preparatory to clearing arm A of that signal, and will thereby deenergize relay 5WS similarly to the manner in which relay 1ES became deenergized at the west interlocking as previously described.

The first westbound traffic control circuit will then be closed, passing from terminal B, through asymmetric unit U2, winding of relay 2RFL, contact 40 of relay 1ES, sections 13-9 to 13-1 of the control conductor and through contact 101TR-39, back point of contact 101S-38, front point of contact 101PC-37, contact 36 of code transmitter 180CT, contacts 102TR-35, 104TR-34, 106TR-33, 108TR-32, back point of contact 31 of relay 5WS, winding of relay 6LFR, back point of contact 43 of relay 5WS, section 14-2 of the return conductor, back point of contact 101S-42, sec-

tion 14-1 of the return conductor, and the front point of contact 41 of relay 1ES to terminal O.

With relay 6LFR energized by current of the 180 code, contacts 47 and 50 of this relay will close alternately at their front and back points at a corresponding speed. Current will therefore be supplied alternately to primary windings 48 and 49 of a transformer T, which will cause alternating current to be generated in the secondary windings 51 and 52 of transformer T, and this will in turn be rectified by contact 59 of relay 6LFR to energize relay 6LFRP. At the same time, current of 180 code will cause the 180DU unit to energize relay 6LAD.

With both relays 6LFRP and 6LAD energized, a circuit, only a portion of which is shown, will be closed for operating arm A of signal 6L to the proceed position, passing through contacts 6LFRP-53, 6LFL-54, front point of contact 6LAD-55, mechanism of arm A of signal 6L, and the front point of contact 6LAD-56 to terminal OO.

With the first westbound traffic control circuit closed, relay 2RFL will be energized, causing its contact 57 to be closed periodically according to the 180 code. A circuit will therefore be completed through this contact for energizing relay 2RFLP. Relay 2RFLP, being of the slow release type, will retain its contact 2RFLP-45 open in the circuit for arm A of signal 2R during the open periods of contact 57 of relay 2RFL.

I shall now assume that a westbound train proceeds over the stretch of track and passes signal 101. Relay 101TR will thus become deenergized, and its contact 19 will open the circuit previously traced for signal 101, causing the arm of signal 101 to indicate stop.

Relay 101PC will therefore become deenergized, but since this relay is of the slow releasing type, its contact 59 will remain closed at its front point for a brief period of time during which a pick-up circuit will be completed for energizing relay 101S, this circuit passing from terminal B, through contact 58 of relay 101TR, front point of contact 59 of relay 101PC, and the winding of relay 101S to terminal O. When contact 59 of relay 101PC moves to its back point, a stick circuit will be completed for relay 101S, passing from terminal B, through the back point of contact 59 of relay 101PC, contact 60 of relay 101S, and the winding of relay 101S to terminal O. With relay 101S energized, a circuit will be completed for energizing code transmitter 75CT, this circuit passing from terminal B, through contact 101S-61, and the winding of transmitter 75CT to terminal O.

When the train leaves section 102T, the second westbound traffic control circuit will be completed, passing from terminal B, through contact 62 of transmitter 75CT, front point of contact 101S-38, sections 13-7 to 13-1 of the control conductor and through the back point of contact 101PC-37 and contacts 102TR-35, 104TR-34, 106TR-33, and 108TR-32, back point of contact 31 of relay 5WS, winding of relay 6LFR, back point of contact 43 of relay 5WS, section 14-2 of the return conductor, and the front point of contact 101S-42 to terminal O. With relay 6LFR thus energized by current of the 75 code, relay 6LFRP will be energized but relay 6LAD will remain deenergized, causing the arm A of signal 6L to now be operated to the caution position by a circuit including contact 6LFRP-53, contact 6LFL-54, back point of contact

6LAD—56, mechanism of arm A, and the back point of contact 6LAD—55 to terminal OO.

From the foregoing description and the accompanying drawings, it follows that by employing coded current of two different frequencies, selected by a directional stick relay and by a signal repeater relay, I have provided means for controlling, over a two-wire traffic locking circuit arrangement, a three-position dwarf signal for controlling reverse running traffic movements over a track on which traffic normally moves in only one direction, as for example, one track of a double track railroad.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a traffic controlling system for governing traffic movements in both directions over a given stretch of railway track between two interlockings one at each end of said stretch, including a control conductor and a return conductor extending between said interlockings with two sources of current one at each of said interlockings normally connected across said conductors in opposition to each other, including a signal adjacent a first one of said interlockings for governing traffic movements approaching said first interlocking from said stretch of track, including a second signal capable of displaying either a caution or a proceed indication as well as a stop indication in the second interlocking for governing traffic movements toward said first signal, and also including a third signal in said first interlocking for governing traffic movements to said stretch of track, the combination comprising a code following lockout relay connected in series with said control conductor at said first interlocking, a code following traffic relay normally disconnected from said conductors at said second interlocking, manually controllable means for at times disconnecting the source of current at said second interlocking from said conductors and for connecting said code following traffic relay across said conductors preparatory to clearing said second signal, means for periodically interrupting at a given frequency the current supplied to said conductors at said first interlocking if said first signal is clear, means for periodically interrupting at a second given frequency the current supplied to said conductors at said first interlocking if said first signal is put to stop by a train approaching said first interlocking from said stretch of track, means controlled by said code following traffic relay for operating said second signal to display the proceed or caution indication according as the current supplied to said conductors at said first interlocking is interrupted at said first or said second frequency, and means controlled by said lockout relay upon becoming energized for opening a control circuit for said third signal.

2. In a traffic controlling system for governing traffic movements in both directions over a given stretch of railway track between two interlockings one at each end of said stretch, including a control conductor and a return conductor extending between said interlockings with two sources of current one at each of said interlockings normally connected across said conductors in opposition to each other, including a signal

adjacent a first one of said interlockings for governing traffic movements approaching said first interlocking from said stretch of track, including a second signal capable of displaying either a caution or a proceed indication as well as a stop indication in the second interlocking for governing traffic movements toward said first signal, the combination comprising a code following traffic relay normally disconnected from said conductors at said second interlocking, manually controllable means for at times disconnecting the source of current at said second interlocking from said conductors and for connecting said code following traffic relay across said conductors preparatory to clearing said second signal, means for periodically interrupting at a given frequency the current supplied to said conductors at said first interlocking if said first signal is clear, means for periodically interrupting at a second given frequency the current supplied to said conductors at said first interlocking if said first signal is put to stop by a train approaching said first interlocking from said stretch of track, and means controlled by said code following traffic relay for operating said second signal to display the proceed or caution indication according as the current supplied to said conductors at said first interlocking is interrupted at said first or said second frequency.

3. In a traffic controlling system for governing traffic movements in both directions over a given stretch of railway track between two interlockings one at each end of said stretch, including a control conductor and a return conductor extending between said interlockings, including a first signal adjacent a first one of said interlockings for governing traffic movements approaching said first interlocking from said stretch of track, including a second signal capable of displaying either a caution or a proceed indication as well as a stop indication in the second interlocking for governing traffic movements toward said first signal, including a third signal in said first interlocking for governing traffic movements to said stretch of track, the combination comprising a code following traffic relay normally disconnected from said conductors, manually controllable means for at times disconnecting the source of current at said second interlocking from said conductors and for connecting said code following traffic relay across said conductors preparatory to clearing said second signal, means for periodically interrupting at a given frequency the current supplied to said conductors at said first interlocking if said first signal is clear, means for periodically interrupting at a second given frequency the current supplied to said conductors at said first interlocking if said first signal is put to stop by a train approaching said first interlocking from said stretch of track, and also including a manually controllable circuit embodying said pair of conductors for at times clearing said third signal, the combination comprising a code following traffic relay normally disconnected from said conductors, manually controllable means for at times opening said first circuit and for connecting said traffic relay across said conductors, means controlled by traffic conditions if there is no train in said stretch of track or routed toward said stretch of track in said first interlocking for supplying current of a given code to said conductors for energizing said traffic relay, means controlled by a train as soon as it has entirely passed said first signal while approaching said first interlocking from said stretch of track for supplying current of a second given code to said conductors for energizing said traffic relay, and means controlled by said traffic relay for operating said second signal to display the proceed or the caution indication according as said traffic relay is energized by current of said first or said second code.

4. In a traffic controlling system for governing traffic movements in both directions over a given stretch of railway track, including a first signal for governing traffic movements in a given direction over a portion of said stretch, including a second signal capable of displaying either a caution or a proceed indication for governing traffic movements from said second signal to said

first signal on said stretch of track, and also including a directional stick relay which becomes energized only if a train moving in said given direction passes said first signal in response to an indication displayed by said first signal, the combination comprising a code following traffic relay, means controlled by a back contact of said directional stick relay for energizing said traffic relay by current of a given code, means controlled by a front contact of said directional stick relay for energizing said traffic relay by current of a second given code, and means controlled by said traffic relay for operating said second signal to display the proceed or the caution indication according as said traffic relay is energized by current of said first or said second code.

5. In a traffic controlling system for governing traffic movements in both directions over a given stretch of railway track, including a first signal for governing traffic movements in a given direction over a portion of said stretch, including a second signal capable of displaying either a caution or a proceed indication for governing traffic movements from said second signal to said first signal on said stretch of track, including a pair of conductors extending between said first and second signals, and also including a directional stick relay which becomes energized only if a train moving in said given direction passes said first signal in response to an indication displayed by said first signal, the combination comprising a code following traffic relay connected across said conductors, means controlled by a back contact of said directional stick relay for supplying current of a given code to said pair of conductors if said first signal is displaying an indication other than stop, means controlled by a front contact of said directional stick relay for supplying current of a second given code to said pair of conductors if said first signal is indicating stop, and means controlled by said traffic relay for operating said second signal to display the proceed or the caution indication according as said traffic relay is energized by current of said first or said second code from said pair of conductors.

6. In a traffic controlling system for governing traffic movements in both directions over a given stretch of railway track, including a signal for governing traffic movements in a given direc-

tion on said stretch, including a second signal capable of displaying either a first or a second indication for directing traffic movements in said given direction on said stretch toward said first signal, and also including a directional relay which becomes energized only if a train moving in said given direction passes said first signal while said first signal is displaying some indication other than stop, the combination comprising 10 a code following traffic relay, means controlled by said directional relay for energizing said traffic relay by current of a given code if said directional relay is deenergized and if said first signal is displaying some indication other than stop, 15 means controlled by said directional relay for energizing said traffic relay by current of a different second code if said directional relay is energized and if said first signal is displaying the stop indication, and means controlled by said traffic relay for operating said second signal to display its first or second indication according as said traffic relay is energized by current of said given or said second code.

7. In a traffic controlling system for governing traffic movements in both directions over a given stretch of railway track, including a signal for governing traffic movements in a given direction on said stretch, including a second signal capable of displaying either a first or a second indication for directing traffic movements in said given direction on stretch toward said first signal, and also including a directional relay which becomes energized only if a train moving in said given direction passes said first signal while said first signal is displaying some indication other than stop, the combination comprising a code following traffic relay, means controlled by said directional relay for energizing said traffic relay by current of a given code if said directional relay is deenergized, means controlled by said directional relay for energizing said traffic relay by current of a different second code if said directional relay is energized, and means controlled by said traffic relay for operating said second signal to display its first or its second indication according as said traffic relay is energized by current of said given or said second code.

JOHN M. PELIKAN.
